CLAIM

The ornamental design for a modular wall frame component as shown and described.

DESCRIPTION

FIG. 1 is a top perspective view of a modular wall frame component showing my new design;

FIG. 2 is a bottom perspective view of the modular wall frame component of FIG. 1;

FIG. 3 is a side elevation view of the modular wall frame component of FIG. 1 with all sides being the same;

FIG. 4 is a top plan view of the modular wall frame component of FIG. 1; and,

FIG. 5 is a bottom plan of the modular wall frame component of FIG. 1.
